(57) **ABSTRACT**

This invention relates to oil refining, more particularly to a composition of a heavy fuel oil for use in marine power units and boiler plants. The fuel comprises, in percent by weight: an extract from the selective extraction of gas oil—(3-5), heavy catalytic cracking gas oil—(3-10), vacuum gas oil—(5-10), tar or topped residuum—(3-10), straight-run black oil—(10-20), viscosity breaking residue of heavy oil fractions—the rest. The selected combination of the components and their ratio may for example, result in a stable heavy fuel oil having improved viscosity properties. The inclusion of the above components into the fuel composition may also make it possible to expand the production of heavy fuel oils produced.

1
HEAVY FUEL OIL

This application is a national phase application of International Application No. PCT/RU2006/000364, international filing date Jul. 11, 2006 which claims priority to Patent Application of Russian Federation No. 2005122581, filed Jul. 18, 2005. These documents are hereby incorporated by reference in their entirety.

BACKGROUND OF THE INVENTION

This invention relates to oil processing, more particularly to a composition of a fuel oil, such as heavy fuel oil that may be used in marine power units and boiler plants.

A heavy fuel oil is known which comprises a distillate of asphalt thermal cracking and a deasphalting residue in the ratio from 30:70 to 50:50 (SU 1575560, C 10 L 1/04, 1999).

However, this fuel may be unstable and does not possess required viscosity-temperature properties.

Another type of available fuel is a heavy fuel oil that comprises a viscosity breaking residue of heavy oil fractions and deasphalting heavy oil fractions in the ratio from 70:30 to 90:10. In some instances, this fuel may contain light oil fractions as described in JP 60-123554, C 08 L 91/00, 1985.

In Russia, however, deasphalting oil fractions are mainly used as raw stock in production of lubricants, and their availability is limited.

Another known heavy fuel oil is based on the viscosity breaking residue of a black oil and tar mixture having the boiling temperature range from 360° C.-KK and comprises 1-5% by wt. of an extract from the process of selective extraction of gas oil, up to 10% by wt. of heavy catalytic cracking gas oil, up to 2% by wt. of a residual component obtained from the process of deasphalting oils with propane, and 0.5-2.5% by wt. of slop wax (RU 2185415, C 10 L 1/04, 2002).

A disadvantage of the said technical solution is that the use of a residual component obtained in the process of oils deasphalting with propane in its composition leads to a significant increase in viscosity and a higher pour point of the fuel.

SUMMARY OF THE INVENTION

Two objectives of the present disclosure are to lower the viscosity and improve the stability of a heavy fuel oil.

Additional objects and advantages of the invention will be set forth in part in the description which follows. The objects and advantages of the invention will be realized and attained by means of the elements and combinations particularly pointed out in the appended claims.

It is to be understood that both the foregoing general description and the following detailed description are exemplary and explanatory only and are not restrictive of the invention, as claimed.

2
DETAILED DESCRIPTION OF THE INVENTION

A fuel oil of the present disclosure comprises viscosity breaking residue of heavy oil fractions, an extract from the selective extraction of gas oil, heavy catalytic cracking gas oil, vacuum gas oil, tar or topped residuum and straight-run black oil in the following component ratio, in percent by wt.:

10	Extract from the selective extraction of gas oil	3-5
	Heavy catalytic cracking gas oil	3-10
	Vacuum gas oil	5-10
	Tar or topped residuum	3-10
	Straight-run black oil	10-20
	Viscosity breaking residue of heavy oil fractions	the rest.

In another embodiment, the fuel oil of the present disclosure may comprise 0.02-0.10% by wt. of a pour-point depressant.

The fuel oil of the present disclosure is characterized by that the fuel composition comprises vacuum gas oil, tar or topped residuum and straight-run black oil in the claimed ratio.

The selected combination of the components and their ratio are able, for example, to achieve a stable fuel oil having improved viscosity properties. Further, the inclusion of the above components into the fuel composition may enable to expand the range of heavy fuel oils produced for marine and boiler plant applications.

In one embodiment, the fuel oil of the present disclosure may be prepared by mixing the components through agitation.

Three specimens of the fuel oil of the present disclosure were prepared according to the said method.

The characteristics of the components used for preparing the said fuel specimens are shown in Table 1.

A tar viscosity breaking residue was used in preparing specimens of the fuel oil of the present disclosure.

In one embodiment, an additive on the basis of copolymers of ethylene and vinyl acetate may be used as a pour-point depressant, for example those known in the field, such as, Paradin-70, ECA-7433. In preparing the fuel specimens the Paradin-70 additive was used.

The compositions of the inventive fuel specimens and their quality indices are shown in Table 2.

The data from Table 2 confirms that the specimens of the fuel oil of the present disclosure may comply with the Specifications for high-viscosity marine fuel oil (TU 3810113114) and with the national standard for boiler plant fuel oil (GOST 10585-75).

It is intended that the specification and examples be considered as exemplary only, with a true scope and spirit of the invention being indicated by the following claims.

TABLE 1

CHARACTERISTICS OF THE COMPONENTS USED FOR PREPARING SPECIMENS OF THE INVENTIVE HEAVY FUEL OIL								
Item	PARAMETERS	Viscosity breaking residue	Extract from selective treatment of oils	Heavy catalytic cracking gas oil	Vacuum gas oil	Tar	Topped residuum	Black oil

	total residue at chemical ageing, %	0.02	0.01	0.005				

The invention claimed is:

1. A heavy fuel oil consisting essentially of the following components, in percent by weight:

20

2. A heavy fuel oil consisting essentially of the following components, in percent by weight:

35

Extract from the selective extraction of gas oil	3-5;
Heavy catalytic cracking gas oil	3-10;
Vacuum gas oil	5-10;
Tar or topped residuum	3-10;
Straight-run black oil	10-20; and
Viscosity breaking residue of Heavy oil fractions	the rest.

40

Extract from the selective extraction of gas oil	3-5;
Heavy catalytic cracking gas oil	3-10;
Vacuum gas oil	5-10;
Tar or topped residuum	3-10;
Straight-run black oil	10-20;
Pour-point depressant	0.02-0.10; and
Viscosity breaking residue of heavy oil fractions	the rest.
